DESIGN FOR A TOY FIGURE

William Pène du Bois, New York, N. Y.

Application September 3, 1936, Serial No. 64,707

Term of patent 14 years

To all whom it may concern:

Be it known that I, William Pène du Bois, a citizen of the United States, residing in New York, county of New York, and State of New York, have invented a new, original, and ornamental Design for a Toy Figure, of which the following is a specification, reference being had to the accompanying drawing forming a part thereof.

In the drawing:—

Fig. 1 is a side view of the toy figure illustrating my new design.

Fig. 2 is a front view thereof.

I claim:—

The ornamental design for a toy figure substantially as shown.

WILLIAM PÈNE DU BOIS.
